Primary Examiner — Eric L Goodman*Assistant Examiner* — Darcey E Heflin(74) *Attorney, Agent, or Firm* — Tucker Ellis LLP; Carlos P. Garritano; Patrick F. Clunk(57) **CLAIM**

The ornamental design for a container for holding a catalyst, as shown and described.

DESCRIPTION

FIG. 1 is a perspective view of a container for holding a catalyst showing a new design;

FIG. 2 is a top view of the container illustrated in FIG. 1; FIG. 3 is a bottom view of the container illustrated in FIG. 1;

FIG. 4 is a left side view of the container illustrated in FIG. 1;

FIG. 5 is a right side view of the container illustrated in FIG. 1;

FIG. 6 is a front view of the container illustrated in FIG. 1; and,

FIG. 7 is a rear view of the container illustrated in FIG. 1. The broken lines in the drawings illustrate the portions of the container that form no part of the claimed design.

1 Claim, 3 Drawing Sheets(56)
